UNITED STATES PATENT OFFICE.

CHARLES E. REED, JR., OF CHICAGO, ILLINOIS.

ELECTRIC SPARKING PLUG.

No. 856,602.

Specification of Letters Patent.

Patented June 11, 1907.

Application filed February 27, 1907. Serial No. 359,565.

To all whom it may concern:

Be it known that I, CHARLES E. REED, Jr., a citizen of the United States, residing at Chicago, in the county of Cook and State of Illinois, have invented a new and useful Improvement in Electric Sparking Plugs, of which the following is a specification.

My invention relates to an improvement in the class of electric sparking-plugs employed in connection with gasolene-engines; and my object is to provide a novel construction of certain features and details of such a sparking-plug whereby the efficiency and reliability of operation of the device shall be materially increased in the particulars hereinafter explained.

In the accompanying drawing, Figure 1 shows a sparking-plug of my improved construction by a view in elevation in position on the combustion-chamber with which it is used, represented in broken sectional elevation; Fig. 2, a view in vertical sectional elevation of my improved sparking-plug; Fig. 3, a broken section taken at the line 3 on Fig. 2, and viewed in the direction of the arrow, and Fig. 4, a view like that presented by Fig. 3, but showing a modification.

The body of the device consists of a chambered head 4, preferably of external hexagonal shape, and having a tubular neck 5 externally threaded to adapt it to screw into the head 6 of the explosion-chamber 7 of a gasolene-engine of known or any suitable construction. The interior of the neck forms the sparking-chamber 8, which is internally threaded at 9 for the purpose hereinafter explained. The positive electrode 10 passes, as usual, through a sleeve 11 of insulating material, which is commonly porcelain, in which it is confined at its projecting ends, as shown, against longitudinal movement. The sleeve passes through the chamber of the head 4, in which it fits at a circumferential flange 12 provided upon it and is confined by a stuffing-box 4^a. The inner end of the wire 10 projects through the head into the sparking-chamber 8, wherein it terminates in a tip 13.

The support for the other electrode is a ring 14 externally threaded to engage the screw-thread 9 and having a depending segment 15 provided with a radial opening 16 into which is driven a head 17 on a neck 18 terminating in a bearing 19 adapted to re-

ceive the lower electrode. In the upper side of the ring is formed a circumferential trough or receptacle 14^b adapted to hold a priming charge of gasolene.

It is most practical to drive the head 17 into the opening 16, to fasten it therein, from the outer side of the segment 15 before providing the thread about the ring, and to then form the screw-thread about the ring and in the segment and head therein to adapt the support for the lower electrode to be screwed into place.

With the ring 14 in place the bearing 19 is in position to receive the lower electrode 20 and support it in vertical alinement with the upper electrode to cause the tip 13 to coincide, at the center of the ring, with the tip 21 in which the electrode 20 terminates. The electrode 20, in the form of a screw, is adapted to be readily adjusted by turning it in its bearing on separating the plug from the head 6 for regulating the space between the tips according to the requirement of the particular coil with which the sparking-plug is employed.

A port 22 leads obliquely from the upper end of the sparking-chamber 8 into a housing 23 formed with an enlargement 24 in its upper portion into which is screwed an annular plug 25 forming an inlet 26 and confining against a spiral spring 28 in the housing a ball-valve 27 which normally maintains closed the inlet 26.

The electrical connection of the sparking-electrodes with a generator and a contact making and breaking device included in the connection, are conventionally represented in Fig. 1.

By the construction thus shown and described, the open-base sparking-chamber is provided entirely within the plug with the terminals in vertical alinement at the center of the open base, whereby when ignition takes place the resultant explosion carries all unburnt carbon downward into the cylinder 7 and thus prevents, as the primary advantage of my improvement, the accumulation of soot in the sparking-chamber. The thoroughness of evacuation of the sparking-chamber of unburnt gas is enhanced, moreover, by the provision of the valved port 22, since each intake-stroke of the piston of the engine opens the ball-valve against the resistance of its sustaining spring sufficiently

to draw air into the sparking-chamber which cleans the latter of all dead gas. Furthermore, the port 22 affords ready access through it to the chamber 8 for cleaning it without requiring the plug to be removed for the purpose or stopping its operation, and for priming the sparking-chamber, through the valve-housing and port, with gasoline, which is received and retained for evaporation in the trough 14; and gasoline may also be readily sprayed through the port into the sparking-chamber for cleaning, when required.

The modified construction represented in Fig. 4 is the simpler and affords the advantages of the construction shown in Figs. 2 and 3. In the modification the ring, shown at 14² and containing a circumferential trough 14¹ like that in the ring 14, is integral with the wall of the neck 5 and the tip 13 of the wire 10 coincides with the center of the ring. The lower electrode 20¹, with its tip 21¹, is substantially like the electrode 20, but screws into and is adjustable in a bearing 19¹ in the wall of the neck, below the external screw-thread thereon, where the screw is countersunk into the wall, as represented, to prevent it from obstructing the insertion of the neck into the head 6. The electrode 20¹ thus occupies a horizontal position and aligns at its inner end with the vertical electrode 10.

What I claim as new, and desire to secure by Letters Patent, is—

1. In a sparking-plug, the combination of a body having a tubular neck forming the sparking-chamber, an upper electrode projecting centrally into said chamber, a ring forming the open base of said chamber, a bearing supported on said ring to align vertically with said upper electrode, and a lower electrode supported in said bearing.

2. In a sparking-plug, the combination of a body having a tubular neck forming the sparking-chamber, an upper electrode projecting into said chamber, a ring forming the open base of said chamber and having a depending segment provided with an opening,

a bearing supported in said opening, and a lower electrode supported in said bearing in vertical alinement with the upper electrode. 50

3. In a sparking-plug, the combination of a body having a tubular neck forming the sparking-chamber, an upper electrode projecting into said chamber, a ring having a depending segment containing an opening with a head confined in the opening, the ring, segment and head being threaded and screwed into said neck to form the open base thereof, a neck extending from said head and terminating in a bearing near the center of said ring, and a lower electrode supported in said bearing in vertical alinement with the upper electrode. 60

4. In a sparking-plug, the combination of a body having a tubular neck forming the 65 sparking-chamber, an upper electrode projecting into said chamber, an annular support for a lower electrode forming the open base of said chamber, a lower electrode on said support in vertical alinement with said upper electrode, and a valved port in the body leading to said chamber. 70

5. In a sparking-plug, the combination of a body having a tubular neck forming the 75 sparking-chamber, an upper electrode projecting into said chamber, a ring forming the open base of said chamber and having a trough in its upper side, a lower electrode supported in said neck, and a valved port in the body leading to said chamber. 80

6. In a sparking-plug, the combination of a body having a tubular neck forming the 85 sparking-chamber, an upper electrode projecting into said chamber, a valve-housing in the body having an opening, a spring-pressed valve in the housing controlling said opening therein, a port leading from said housing into the sparking-chamber, a ring forming the open base of said chamber, and a lower electrode supported in said neck.
